UNITED STATES PATENT OFFICE

WILLIAM H. LEAVIN, OF NEW YORK, N. Y., ASSIGNOR TO GOTHAM KNITBAC MACHINE CORPORATION, OF NEW YORK, N. Y., A CORPORATION OF DELAWARE

MACHINE FOR REPAIRING RUNS IN FABRICS

Application filed August 14, 1929. Serial No. 385,877.

This invention relates to the art of repairing runs in knitted and woven fabrics such as stockings and the like.

One of the objects of this invention is the provision of a machine for automatically re-knitting or reweaving the threads of a fabric which have become unwoven or unknitted causing a so-called run.

One of the objects of this invention is the provision of mechanism for feeding the fabric with the cross threads of the run held in proper spaced relation and means for interlocking or weaving the cross threads of the run to repair it.

The prime object of this invention is the provision of a machine of this type in which a number of parallel runs may be repaired.

An additional object of this invention is the provision of a machine having a plurality of oscillating needles arranged to repair a plurality of parallel runs simultaneously.

Another object of the invention is the provision in mechanism of this type of means for properly holding the fabric under correct tension with the threads which cross the run fixed in the proper spaced relation so that one or a plurality of needles may operate thereon to repair one or a plurality of parallel runs in the fabric.

Another object of the invention is the provision of operating mechanism for moving the feeding means and the needles in the proper timed relation so that the needles will descend between the cross threads of the run at the proper time, be withdrawn therefrom, and the fabric advanced all in the correct timed relation.

These and many other objects which will appear from the following disclosure are successfully secured by means of this invention.

This invention resides substantially in the combination, construction, arrangement, and relative location of parts all as will be described in greater detail hereinafter.

Referring to the drawings in which the same reference numerals will be used in the various figures to indicate the same or similar parts

Fig. 16 is an enlarged plan view of a modified form of mechanism for repairing three parallel runs showing the relative arrangement of the three needles with respect to the feeder wheels, the spacer wheels, the presser feet and the spring finger which bears on the cross-threads of the run:

This invention is of the general nature shown in the issued patent to William H. Leavin and Samuel B. Leavin, No. 1,708,675 dated April 9, 1929. The invention involves

an operative association of elements by means of which the runs in knitted and woven fabrics may be repaired by reknitting so as to completely repair the fabric without leaving any indicating marks that such a repair has been made. The description of the use and operation of this machine will be made in connection with runs such as commonly occur in ladies' silk stockings. As is well known, such a run usually occurs by the breaking of a thread, and usually only extends transversely of the length of the run to the extent of one wale. The run begins at the point of the broken thread and continues to the stopping point being caused by an unraveling of the interlocked threads. The machine of the above mentioned patent while involving the basic principles of the machine of this invention is more particularly adapted for repairing a run in such fabric which is of the width of one wale and which is known as a single run.

It quite frequently occurs, however, that the threads are so broken in a silk stocking that the run is of the width of two or more wales and is known as a double, triple, or multi-run, depending upon the width of the run. In a machine of this nature a single needle only repairs a run of the width of one wale. The device of this invention therefore contemplates an association of elements employing a plurality of needles by means of which a plurality of runs of single wale width may be repaired simultaneously. It is also pointed out that these multiruns which comprise a series of single runs of one wale width do not extend for the same distance throughout the full width thereof. In other words, in a multirun the runs in the parallel wales which, although generally adjacent, do not all extend the same distance. For this reason the instrumentalities comprising this invention are arranged so that the single wale runs may be repaired individually, and at the transverse point where one run comes up to an adjacent run other needles as needed may be brought into play so that as the repair progresses the entire multirun may be repaired.

When a run does occur in fabric of this nature the transverse threads of the fabric which are interlocked progressively in a longitudinal direction become disengaged from each other and leave a long narrow strip in the fabric bounded by the knitted fabric on each side which is connected by a series of parallel transverse threads giving a ladder like appearance. The machine of this invention operates to again interweave or interlock these transverse threads to eliminate the run and repair the fabric.

With this basic background reference will now be made to the drawings.

As shown in Figure 1 the device comprises a hollow standard 1 having a supporting base 2 and two integral hollow and substan-

tially parallel arms 3 and 4. Journalled transversely in the standard 1 is a rotatable shaft 4' having a cam 5 and a fly-wheel and pulley 6 secured thereto. The pulley is connected by the belt 8 to a suitable source of power such as a small electric motor 7 which is supported by a bracket 7' on the standard 1. Encircling the eccentric cam 5 is a collar 5' which rides on the periphery thereof and which has the oppositely extending arms 9 and 10. Pivottally mounted on the ends of arms 9 and 10 are the collars 11 and 12 respectively, which adjustably engage the levers 13 and 14 respectively. Lever 13 is pivoted at 15 within arm 4, and lever 15 is pivoted at 16 within arm 3. A hollow head 17 is secured to the outer end of arm 3.

Referring to Fig. 3 there is shown pivotally supported on the end of lever 13 a small pawl 19 which is caused to engage the teeth of the ratchet wheel 21 by means of the leaf spring 20. Ratchet wheel 21 forms part of and is securely fastened to the feeding head unit more clearly shown in Figs. 6 and 7. As shown in Fig. 6 the arm 4 is bifurcated at its outer end to provide the parallel supporting arms 22. Mounted on a hollow central spindle 23 is the disk 24 having a thin peripheral flange 25 which has a smooth peripheral edge, spacer wheels 26, one on each side of the disk 24 with the peripheral teeth 26^a, and the feeder wheels 27 one on each side of the spacer wheels which fit within recesses formed therein. The peripheries of the feeder wheels 27 are roughened or knurled. All of these elements including the ratchet wheel 21 are rigidly secured together to form a unit called the feeding head which is rotatively supported on the short shaft 28 secured within the arms 22 by means of screws 29 which also hold the cover plates 30 in place. The peripheries of the feeder wheels 27 are adjacent the bases of the spacer teeth 26^a as clearly shown in the drawing, and the periphery of the flange 25 is likewise in approximately the same plane. As will be apparent from Fig. 6 the feeder head rotates as a unit on the hollow spindle 23. This unit rotates in a clockwise direction as viewed from Figs. 1, 3 and 5. Secured to one of the arms 22 and within a cylindrical recess in one of the feeder wheels 27 is the bar 31 having inclined ends as clearly shown in Fig. 8. Spring clips 32 rotatively hold small rollers 33 between the inclined ends of the bar 31 and the cylindrical inner wall of the recess in the feeder wheel 27. With this arrangement the feeder head unit may rotate in a clockwise direction, as pointed out above, or a counter-clockwise direction as viewed in Fig. 8, but is prevented from operating in a reverse direction by means of these rollers which jam in the space between the ends of

the bar 31 and the cylindrical wall of the feeder wheel.

As shown in Figs. 3 and 4 there is secured to the end of lever 14 a small collar 34 which encircles the hollow rod 35 and is adjustably secured thereto. The hollow rod 35 is vertically slideable in the head 17 and the length of its vertical stroke may be varied by adjusting the position of collar 34 thereon. Slidably supported within the hollow rod 35 is the needle bar 36 which has a manually operable cam member 35 pivotally supported on the end thereof so as to engage the upper end of hollow rod 35. By this arrangement the rod 36 and the needles which are secured thereto, as will be described, may be raised up and down within the hollow rod 35 when desired. Also supported within the head 17 are two rods 38 and 39 which may be vertically adjusted therein by means of the adjusting screws 40. Secured to the needle bar 36 as shown more clearly in Fig. 5, is a yoke member 41 having a transverse rod 54 supported therein. Pivotally supported on the nod 54^a are the small blocks 54 and 55 in which are secured the needles 52 and 51. As will be apparent in connection with the machine under description two needles are employed. Of course with suitable and obvious modifications of this structure any reasonable number of needles may be employed. An adjusting nut 50 is provided on shaft 54^a so that the needles may be adjusted to any desired position and then rigidly fixed in place. When a needle is not in use it may be swung to the dotted position shown in Fig. 3 and locked in that position.

Adjustably secured to the lower end of rod 38 is an arm having the branches which terminate in the presser feet 56 which overlie and lightly contact with the roughened surfaces of the feeder wheels 27. Also secured to the lower end of rod 38 is an arm 57 which terminates in a very thin narrow spring finger which in operative position contacts lightly with the periphery of flange 25. The position of the presser feet with respect to the feeder wheels and the spring finger 58 with respect to the flange may be adjusted by means of adjusting nut 40. For sake of clarity in Fig. 5 spring finger 58 is shown in raised position out of contact with the flange but, of course, in operative position it will contact lightly with the flange. As is clear in Fig. 12 spring finger 28 is of about the same width as flange 25 and lies between the needles 51 and 52. Adjustably secured to the lower end of rod 39 is a bracket 59 which rotatively supports a roller 60 which is of reduced diameter at the central part so as not to contact with teeth 26^a but which near its ends is of sufficient diameter to contact, or almost contact, with the roughened surface of the feeder wheels 27. This position

with respect to the feeder wheels may be adjusted by means of nut 40. As is clear in the various figures and particularly in Fig. 14, the presser feet 56 are cut away on their lower surfaces as shown at 56^a at a point a little in advance of the vertical axis of the needles so that the threads T which traverse the runs are relatively free from movement as the needle moves vertically between them. In connection with Figs. 14 and 15 it may be well to know at this time the shape of the teeth 26^a which are substantially straight on their forward edges, inclined on their rear edges and meet in a smooth curve which is a little forward of the tooth. This form of construction has been found very efficient for rapidly causing the transverse threads T of the run to fall to the base of the teeth one between each two adjacent teeth.

A modified form of needle bar arrangement is shown in Figs. 9, 10 and 11. The hollow rod 35 is employed as before and is arranged to slide vertically in the head 17. Within the hollow rod are two half round needle holding bars 70 and 71 provided with handles 72 and 73 respectively, by means of which they may be slid vertically within the hollow rod 35. As shown in Fig. 9 the left hand bar 71 is in raised position with the needle 52 withdrawn. Between the two bars 70 and 71 is a flat piece of spring metal 74 having the ears 73 which rest on the top of the hollow rod 35. Spring fingers 76 are struck up from the strip 74 in opposite direction so as to frictionally engage the bars 70 and 71 to hold them in any desired position. As before, the collar 34 is secured to lever 14. By means of this arrangement either or both the needles may be raised or lowered so that either one alone, or both, may be used to operate on the fabric.

A detailed view of an arrangement for employing three needles is shown in Fig. 16. The feeder wheels 27 are employed as before, as well as the spacer wheels 26 with their teeth 26^a. In front of the two needles 51 and 52 and centrally thereof is a third needle 58. The presser feet 56 are employed as before, but it is to be noted that the spacing disk 24 is not employed. In this case the spring finger 58 attached to the arm 57 is provided with a U-shaped portion at its end providing the fingers 59. With this arrangement any number of runs one wale in width up to three may be repaired.

The operation of the device will now be described. It is usual in this work to repair a run by picking up the loop at the end of the run where the unraveling stopped and to re-knit the run back towards the point of beginning. The fabric is therefore placed on the feeder head unit so that the threads at the end of the run lie between the teeth 26^a of the spacer wheels one between each two adjacent teeth. These threads T (Figs. 14 and 15) ex-

tend transversely of the feeder head unit so that they lie between the two spacer wheels. When the motor 7 is started cam 5 revolves and levers 13 and 14 oscillate. The oscillation of lever 13 causes the rotation of ratchet wheel 21 through the engagement of its teeth with pawl 19. The rotation of the ratchet wheel causes the entire feeder head unit to revolve in a counter-clockwise direction (see Fig. 3). As a rule the transverse threads of the run lying between the teeth 26^a are moved towards the needles. The fabric moves under the presser feet and is held firmly against the roughened surfaces of the feeder wheels 27. As the cross threads of the run arrive at the line of vertical oscillation of the needles the needles descend between two adjacent cross threads. It is, of course, understood that the loop at the end of the run is hooked over the needle hook indicated, for instance, at 52^a (Fig. 14). The needle descends far enough as shown in Fig. 14 so that the loop formed by the cross threads slips up over the latch 56^b of the needle. As the needle is withdrawn upwardly its hook catches onto the next cross thread and upon continued movement that cross thread is drawn up through the previous loop which loop closes the latch 56^b of the needle as the needle is withdrawn. Thus that cross thread is drawn up through the previous loop which slips down off the hook. With the needle withdrawn the feeder head unit advances the proper distance so that upon the next descent of the needle it will pass between the next cross threads of the run. Thus one at a time the cross threads are looped through the preceding loop and the fabric is repeatedly repaired. Of course, at the end of the run the last loop must be secured by sewing, or in some similar manner. It is emphasized again that the bottom of the presser feet is cut away as shown at 56^a so that the fabric is relatively free at the point where the needle operates. Past this point as shown in Fig. 3 for example, the fabric is again held against the roughened surfaces of the feeder wheels by roller 60. In the case of the two needle machine shown if the run is only one wale in width one needle is thrown to the dotted position shown in Fig. 3 until the run becomes two wales in width then both needles will be in operative position. When both needles are operating in order to have two rows of loops formed it is necessary to in effect keep the two fields of action of the needles separate. This is accomplished by the spring finger 58 (Fig. 12) which lies between the needles 51 and 52 and holds the cross threads of the run at their center point in firm contact with the peripheral edge of flange 25 on disk 24. In the case of where a run of three wales in width is being repaired and three needles are operating the three lines or fields of action of the needles are kept separate by means

of the spring finger 58' (Fig. 16) having the branch fingers 59. When desired the needle bar may be raised by the manually operated cam 37 or the hand lever 19 (Fig. 2). This hand lever has not been described here since it is fully disclosed in the above mentioned patent and comprises nothing new in connection with this invention. As is already clear from this patent the presser feet hold the fabric in proper position in conjunction with the spacer wheels with respect to the needles and under the proper tension so that as the run is repaired no unsightly line or mark is left.

From the foregoing description it will be apparent that I have embodied certain new and novel principles of construction and operation in a device for repairing so called multiruns in knitted and woven fabrics. I am, of course, aware that many changes in the detail of construction and relative arrangement of parts will readily occur to those skilled in the mechanical arts without departing from the spirit and scope of the invention as involved in those principles. I do not, therefore, desire to be limited to my disclosure which is given in an illustrative sense but rather to the scope of the appended claims.

What I seek to secure by United States Letters Patent is:

1. In a machine for repairing runs in knitted fabrics and the like, the combination comprising means for supporting the fabric with the threads that traverse the run in spaced relation, means for causing the movement of said means, and means including a plurality of needles for successively looping the cross threads of the run one with another to form parallel lines of repair in the fabric.

2. In a machine of the type described for repairing runs of a plurality of wales in width in knitted fabrics and the like, the combination comprising rotatable means for supporting the fabric with the cross threads of the run in spaced relation, a movable member, a plurality of needles on said movable member, and means for rotating said rotatable means in a step by step movement and for moving said needles with respect to the fabric to successively form a plurality of interlocking loops between the cross threads of the run to form parallel lines of repair in the fabric.

3. In a machine for repairing runs in knitted fabrics and the like in which the runs are of several wales in width, the combination comprising toothed spacer wheels supported for rotation, said spacer wheels being adapted to receive the transverse threads of the runs between the teeth thereof, means for holding the transverse threads between the teeth, means including a plurality of needles one for each wale involved in the run, and means for rotating said spacer wheels in step by step movement and for moving the needles with respect

- to the fabric to effect a successively looping of the transverse threads of the run to form parallel lines of repair in the fabric.
4. In a device for repairing two adjacent runs in a knitted fabric, the combination comprising two oscillatable needles, rotatable means for supporting the fabric with the threads that cross the runs in spaced parallel relation, means for oscillating the needles and for rotating said rotatable means, and means for gripping the threads which traverse the run between the needles.
5. A rotatable feeding head unit of the type described, comprising two toothed spacer wheels, a disk between said wheels for holding them in spaced relation having a peripheral thread supporting flange and feeder wheels over-lying the outside faces of the spacer wheels, all of said elements being rigidly secured together to form a unitary structure.
6. A rotatable feeding head unit of the type described, comprising two toothed spacer wheels, a disk between said wheels for holding them in spaced relation having a peripheral thread supporting flange and feeder wheels over-lying the outside faces of the spacer wheels, all of said elements being rigidly secured together to form a unitary structure and a ratchet wheel secured to the unitary structure.
7. The combination comprising a support, a unitary feeder head rotatably secured to said support comprising a disk having a peripheral thread supporting flange, spacer wheels at the sides of said disk, feeder wheels with roughened surfaces enclosing said spacer wheels, and means for securing the disk, spacer wheels, and feeder wheels together to form a unitary rotatable structure.
8. The combination comprising a support, a unitary feeder head rotatably secured to said support comprising a disk having a peripheral thread supporting flange, spacer wheels at the sides of said disk, feeder wheels with roughened surfaces enclosing said spacer wheels, means for securing the disk, spacer wheels, and feeders wheels together to form a unitary rotatable structure, and a ratchet wheel secured to said unitary structure for rotation therewith.
9. In a machine for repairing runs in knitted fabrics and the like, the combination comprising a support, a rotatable feeder head mounted on said support including toothed spacer wheels held in spaced relation by means of a flanged thread supporting disk, a needle bar supporting a plurality of needles slidably mounted in said support, and means for rotating said spacer wheels and disk and for moving the needle bar and its needles with respect thereto.
10. In an apparatus of the type described for repairing a plurality of runs in knitted fabrics and the like, the combination comprising means for supporting the cross

threads of the run in spaced relation, a needle bar supported for movement with respect to said means, a plurality of movable needles supported on the needle bar, means for gripping the cross threads between the lines of action of the needles, and means for rotating said means for supporting the fabric and for moving said needle bar and needles, said needles being adapted to be moved out of operative position at will.

11. In a machine for simultaneously repairing a plurality of runs in knitted fabrics and the like, the combination comprising rotatable means including two toothed spacer wheels supported by a flanged disk, a movable needle bar, two needles supported on said needle bar, means for imparting step by step movement to the spacer wheels, means for moving the needles with respect to the spacer wheels, and means cooperating with the flanged disk for firmly holding the threads which traverse the runs between the lines of action of the needles.

12. In a machine for simultaneously repairing a plurality of runs in knitted fabrics and the like, the combination comprising rotatable means including two toothed spacer wheels supported by a flanged disk, a movable needle bar, two needles supported on said needle bar, means for imparting step by step movement to the spacer wheels, means for moving the needles with respect to the spacer wheels, means cooperating with the flanged disk for firmly holding the threads which traverse the runs between the lines of action of the needles, and means for holding the fabric under the proper tension and for feeding it to the needles so that the threads which traverse the runs are presented successively to the needles.

13. In a machine for repairing a plurality of runs in knitted fabrics and the like, the combination comprising movable means for supporting the fabric with the threads which traverse the runs in spaced relation and for feeding the fabric, a movable needle support, a plurality of needles secured to said needle support, means for operating the supporting and feeding means, means for moving the needle support and its needles, and means for securely holding the threads which traverse the runs at a point between the line of action of each two adjacent needles.

In testimony whereof I have hereunto set my hand on this 13th day of August A. D., 1929.

WILLIAM H. LEAVIN.
